UNITED STATES PATENT OFFICE.

CHARLES SEARS, OF CLEVELAND, OHIO.

MATRIX-MAKING MACHINE.

SPECIFICATION forming part of Letters Patent No. 508,248, dated November 7, 1893.

Application filed April 25, 1892. Serial No. 430,573. (No model.)

To all whom it may concern:

Be it known that I, CHARLES SEARS, a citizen of the United States, residing at Cleveland, in the county of Cuyahoga and State of

Ohio, have invented certain new and useful Improvements in Matrix-Making Machines; and I do hereby declare the following to be a full, clear, and exact description of the invention, such as will enable others skilled in the art to which it appertains to make and use the same.

My invention relates to improvements in the class of matrix making machines having a revolving cylinder, which carries one or more rows of radially movable dies, a movable matrix carrier which is adapted to be moved at intervals in fixed relation to the cylinder, and any selected one of the dies carried thereby, which relation is determined by the depression of a finger key corresponding with the selected die, and mechanism for causing an impression of said die in the matrix to be made during the time the cylinder and matrix carrier maintain said fixed relation.

The drawings show in all its detail a complete and operative machine containing my invention. Some of the parts of the machine shown are substantially the same as are shown and described in Letters Patent Nos. 475,804, 475,805, 475,806 and 475,807, granted to me May 31, 1892; indeed the machine shown in this application is a development of and improvement in many respects upon the machines shown in said prior Letters Patent.

The principal improvements which the machine hereinafter described embraces relate to the mechanism for moving the matrix carrier in fixed and predetermined relation to the cylinder and the selecting die; to the die moving mechanism; to the mechanism for changing the relative position of the matrix carrier and the several rows of dies carried by the cylinder whereby the dies in any row may be employed to make the impression; to the type-writer attachment; to the mechanism for feeding one matrix strip after another into the machine; to certain safeguards intended to prevent the improper action of the machine as I will hereinafter describe;—all of which improvements will be definitely pointed out in the claims.

The objects of all these improvements in

the several parts of the machine are to simplify its construction and render its action more certain and efficient for its intended purpose.

I will describe in detail the machine shown in the drawings, notwithstanding the fact that the general features are not new, because, since the machine contains a large number of parts, I believe the several improvements which are carefully distinguished in the claims, their mode of action, and their relation to each other and the other parts of the machine will thereby be more clearly understood.

In the drawings, Figure 1 is a top plan view of said machine. Fig. 2 is a front elevation. Fig. 3 is a vertical longitudinal section through the center of the machine. Fig. 4 is an elevation from the left end of the machine. Fig. 5 is a transverse vertical section on line 5—6 viewed from the left of Fig. 2. Fig. 6 is a transverse vertical section on said line 5—6 viewed from the right. Fig. 7 is a transverse vertical section on line 7—7 viewed from the right of Fig. 2. Fig. 8 is a detached view of one of the longitudinally movable rods carried by the cylinder. Fig. 9 is a plan of a part of the cylinder showing ends of the dies, and of the type which are carried thereby. Fig. 10 is a longitudinal section through a part of one side of the cylinder. Fig. 11 is a detached view of the metal bushing through which the dies slide. Fig. 12 is a detached view of the rubber bushing of said dies. Fig. 13 is an end view of three dies in one row, showing the relative position of the characters and size of projections. Fig. 14 is a view of the devices which connect the swinging frame with the die wheel, and which hold said frame in its retracted position, and by which it is released therefrom, the view being from the right side of the machine from which the cylinder has been removed. Fig. 15 is a side view of the upper end of the plate. Fig. 16 is a face view of the plunger mechanism attached to the swinging frame. Fig. 17 is a view of said mechanism seen from the right of Fig. 16. In both of the last two views the plunger and its parts are in the positions they assume when they have forced the die out of the cylinder to make its impression. Fig. 18 is a vertical section at the point indi-

cated by line 18—18 of Fig. 16, when the plunger and its parts are in their normal positions. Fig. 19 is a horizontal section of the plan indicated by line 19 of Fig. 3 with the cylinder removed. Fig. 20 is a top view of the matrix holder when removed from its connection with the swinging frame. Fig. 21 is a front view of the same. Fig. 22 is a vertical section on lines 22—22 of Fig. 20. Fig. 23 is a horizontal section on line 23 of Fig. 21. Fig. 24 is a back view of said mechanism. Fig. 25 is a front view of the movable type writer frame. Fig. 26 is an enlarged section on line 26 of Fig. 25. Fig. 27 is a plan view of the carriage. Fig. 28 is an end view of said carriage seen from the right side. Fig. 29 is an end view from the right of the swinging frame. Fig. 30 is an under side view of the swinging frame. Fig. 31 is a perspective view of a matrix partially finished.

In the drawings, three principal scales are used. Figs. 1, 2, 3, 27, 28, 29 and 30 are quarter size; Figs. 4, 5, 6, 7, 19 and 25 are half size; and Figs. 8, 9, 10, 11, 12, 13, 14, 15, 16, 17, 18, 20, 21, 22, 23 and 24 are full size; Fig. 26 is twice full size.

Referring to the parts by letter, A represents the bed plate of the machine. At one end of this bed plate is secured a standard a^1 having at its upper end a long sleeve a^1 . The driving shaft a^2 is journaled in this sleeve. At one end of the shaft are the fast and loose pulleys a^3 a^4 upon which the driving belt runs.

B represents a hollow cylinder having, at or near its longitudinal center, a hub b^2 which is keyed or otherwise fixed to the driving shaft.

Near one end of the cylinder are one or more rows of radially movable dies C, and near these dies are an equal number of rows of types F which project radially from the cylinder. Set below the surface of the cylinder, in appropriate longitudinal grooves, are the longitudinally movable rods D which pass through the end flanges b^1 b^2 of the cylinder. In a part of their length at least, these rods are made square (as at d) or of any other angular form, and the grooves in the cylinder in which they lie are similarly shaped whereby the rods are prevented from turning. On the ends of these rods which lie outside of the right hand flange b^2 are the heads d' , the purpose of which will be hereinafter explained.

Projecting radially outward from each rod is a beveled arm d^2 . These arms project from the cylinder in a spiral and each is so placed that it will, as the cylinder is revolved, strike its associated bar e^3 when the same is moved out by the operation of its key.

The cylinder is made of two separable parts which are connected by means of bolts as shown in Fig. 3. The right hand end of the cylinder is that part of the cylinder from which the arms d^2 project, and is permanently fixed in the described relation to the

other parts. The left hand end of the cylinder carries the dies C, and type F, and may be removed and another similar part substituted therefor whenever one desires to use a different size or style of type. When in their normal condition, the left ends of the rods D do not project beyond the left end of the cylinder, but each is made to project therefrom to cause the engagement of the swinging frame (to be hereinafter described) with the cylinder, by the operation of its associated key.

The key board and the operating parts connected therewith are supported by two brackets a^5 a^6 which are attached to the bed plate. A cylindrical rod e is secured to said brackets and extends through the left bracket a^5 . Between the brackets, the keys E are loosely hung on the rod e , being separated by washers.

e' represents a round rod which is fastened at its ends to the brackets a^5 a^6 . On it are mounted the bell crank levers e^2 . One arm of each of these levers is connected with a sliding bar e^3 which is supported in and guided by the cross pieces e^5 . This cross piece is connected at its ends with the brackets a^5 a^6 . The other arm of the bell crank lever is connected by means of a link e^4 with one of the keys. The springs e^6 , each connected with a key and with a rod e^7 , exert their force to return the parts to their normal positions as shown in Fig. 7. An angle lever e^8 is mounted loosely on the rod e just to the left of the bracket a^5 . A bar e^9 which lies against the upper side of the keys is rigidly connected at one end to the upper arm of the lever e^8 , and at the other end to an arm similar to said upper arm, which is also loosely mounted on the rod e , near the bracket a^5 .

J represents a lever mounted loosely on a pin secured to the bracket a^5 . Its lower end lies in a position where it is adapted to enter one of the notches j in a bar j' . Its upper end is in contact with the lower arm of the bent lever e^8 . Mounted in the brackets a^5 a^6 is a locking bar e^{10} to one end of which a rigid arm e^{11} is fastened. A link e^{12} is pivoted at one end to the lower arm of the bent lever e^8 , and a pin on the arm e^{11} passes through a slot in said link e^{12} . A coiled spring J^2 is stretched between and connects the arm e^{11} and upper end of the lever J. Secured to the locking bar e^{10} is a flange e^{13} which lies directly in front of the lower edges of the bosses E' on the under side of all of the key levers. Each of these bosses is notched horizontally as shown in Fig. 7.

The mode of operation of the key board mechanism, above explained, is as follows: When a key is depressed by the operator, the key bar e^8 is, by means of the connecting mechanism described, thrust outward into the path of the beveled arm d^2 with which it is intended to co-operate. The movement of the key lifts the bar e^9 which causes the bent lever e^8 to be rocked. The lower end of this bent lever engages with the lever J which is

thereby rocked and its lower end forced into one of the notches *j*, if the bar *J'* is in the right position to permit this movement. If it is not, and the lower end of the lever *J* 5 cannot enter one of the notches *j*, the key *E* cannot be depressed far enough to throw out the key bar *e³*. This is a safe-guard to prevent the operation of the machine, unless the guide for the dies *C* is in such a position as 10 will permit one of the dies to enter it smoothly, as will be presently explained. Before a key is struck, the pin on the arm *e¹¹* abuts against the end of the slot in the link *e¹²*, and the locking bar *e¹⁰* is thereby prevented from so 15 rocking as to throw the flange *e¹³* toward the key bosses *E'*; but when the bent lever *e⁸* has been moved, as before explained, the arm *e¹¹* is permitted to move and is moved by the action of the spring *J²*. The flange *e¹³* on the 20 locking bar enters the notch in the depressed key and thus holds said key down until it is released in the manner to be described; and at the same time the said flange moves beneath the bosses on all the other keys and 25 prevents any of them from being depressed until the locked key is released. The key is released and the parts returned to place by means of a bell crank lever *L* which is pivoted to the under side of the bed plate *A*, an 30 arm *e¹⁴* which is rigidly attached to the locking bar, and a link *e¹⁵*, which connects one arm of the bell lever *L* with said arm *e¹⁴*. The bell crank lever *L* is rocked after an impression has been made by the movement of 35 a bar *I*, thereby causing the locking bar *e¹⁰* to be moved back with the result of disengaging the flange *e¹³* from the key bosses and returning said locking bar to its first position. The spring *J²* will now draw upon the 40 lever *J* which in moving to its first position likewise moves the bent lever *e⁸*, and the bar *e⁹*, attached thereto back to their normal positions.

A sliding carriage *H* (shown separately in 45 Figs. 27 and 28) is mounted on the bed plate in suitable guide ways. This carriage supports the matrix carrying and feeding mechanism, the mechanism for operating the dies, and numerous other parts of the machine to 50 be hereinafter explained. At one end of the carriage is a standard *h*, and to this standard a horizontal arbor *h'* concentric with the cylinder *B* is secured. A swinging frame is mounted on this arbor, and is adapted to 55 swing freely backward and forward in the manner and for the purpose set forth. Around the hub *G* of the frame, a coiled spring *G'* is placed, and the ends of this spring are connected respectively with said hub and with 60 the standard *h*. When the frame is moving forward in fixed relation with the cylinder, the coil is tightened, whereby, when the frame is released, it is moved by the spring back to its first position. The frame consists 65 of three essential parts, viz.,—the hub *G*, the bed plate *g* which lies beneath and more or less nearly parallel to the face of the cylinder,

der, and an arm *g'* which rigidly connects said parts. The matrix holder is secured to the bed plate, and suitable mechanism is provided 70 whereby the frame is connected with the revolving cylinder when the selected die is directly over the matrix, and the frame and cylinder are moved in fixed relation with each other for a time; during which time the die 75 is moved outward and its impression made in the matrix.

The mechanism shown for making this connection consists of the following combination and arrangement of parts: Fixed to the bed 80 of the frame is a bracket *g²*. A rock shaft *g³* is journaled in this bracket and in the arm *g'* of the frame. Rigidly connected with this shaft are two arms *g⁴ g⁴*, and two rods *g⁵ g⁶* are connected at their ends to said arms, and 85 pass through slots in the arm *g'* and bracket *g²*, as shown in Figs. 6 and 14. Loosely pivoted on the rod *g⁶* is a plate *g⁷* which lies close to the end of the cylinder *B* and is held in the proper relation thereto by a pin *g⁸* which projects into the cylinder and bears against its inner wall, and two flanges *g⁹ g⁹* which engage with the sides of the peripheral end flange *b* of the cylinder. The plate has a shoulder *g¹⁰* against which one of the rods *D* strikes when 90 it has been moved out by the described action of its associated key. To prevent recoil, a latch *g¹¹* is provided which is also loosely pivoted on the rod *g⁶* and is held in operative relation with the plate *g⁷* by the head of a screw 95 which passes through a slot in said plate and screws into the latch. The upper end of the latch is beveled, whereby that rod *D* which is projecting from the cylinder is enabled to crowd back the latch until such time as the rod 100 strikes the shoulder *g¹⁰*, at which instant a spring *g¹²* forces the latch over said pin as shown in Fig. 14. Projecting downward from the front edge of the bed *g* is a beveled lug *g¹³*, and pivoted to the carriage *H* is a spring actuated arm *h²* which, when the swinging frame 110 is returned to its normal position, is automatically pushed back by said lug, and then springs beneath it and prevents the forward movement of the swinging frame. Secured to the rock shaft *g³* is a toe *g¹⁴* which is adapted to push the spring arm *h²* from beneath the lug *g¹³* when the rock shaft is rocked. A spring *g¹⁵* secured at one end to the bed *g*, is 115 curved under the rod *g⁵* and serves to hold the rock shaft, and parts connected thereto, in the position shown in Fig. 14—that is to say, it lifts the rod *g⁵* to the top of the slots in the arm *g'*,—the arm *g⁴ g⁴*, to which the rod *g⁵* is attached, and the rock shaft *g³*, to which 120 said arms are attached, being moved in consequence thereof. The plate *g⁷* is cut away for a part of its length in front of a part of the end of the cylinder, whereby one of the rods *D* may be so moved as to project from 125 the end of the cylinder. The upper end of the plate curves away from the cylinder, so that if one of the rods has by accident been moved out from any other point except that 130

opposite to the cut-away part of said plate, said rod will engage with the inclined face of said plate and be thereby thrust back again. When, by the operation of one of the keys, a 5 rod D has been caused to project from the end of the cylinder, it engages against the shoulder g^{10} on the plate g^1 and it is latched by the latch g^{11} . The first effect of this engagement is to rock the rock shaft g^8 , and this 10 causes the toe g^{14} to push back the spring arm h^2 , thereby releasing the swinging frame. The frame then moves in fixed relation with the cylinder for about one sixth of its revolution. The parts are in such relation to each 15 other that when the swinging frame and cylinder are so moving, the die corresponding to the key which was struck to move out the projecting rod is directly over the opening in the matrix holder; and during the time the frame and 20 cylinder preserve their fixed relation, the said die is moved out, its impression is made in the matrix, and it is retracted by the mechanism provided for this purpose. When this has been done, a beveled arm a^7 fixed to the 25 sleeve a^6 engages behind the head d' of the projecting rod D and draws it into the cylinder. This releases the swinging frame, which is then returned to its first position by the spring. In order that a swinging frame may 30 not be unduly strained by the pressure of the die upon the matrix, a friction roller h^8 is journaled to the carriage H directly beneath the opening in the matrix holder when the die is making the impression, and a flange g^{20} , on 35 the under side of the bed of the swinging frame, rides upon the roller. Mounted on guides g^{16} on the ends of the hub G of the swinging frame is a radially movable plunger R which is slotted in both directions. In the 40 slots which are longitudinal with reference to the machine, lie the retracting fingers r^7 which are pivoted to said plunger. Passing through the transverse slots is a bar r' secured rigidly to the swinging frame having beveled upper and lower edges. On the face of a bracket h^3 secured to the head is the cam groove h^4 , into which a pin r^2 secured to the plunger projects. When the swinging frame 45 is stationary, this pin lies at the extreme right 50 hand end of the groove, and below the spring actuated switch h^5 ; and the bar r' lies between two lugs r^6 on the fingers r^7 below their pivots, whereby said fingers are held apart at their lower or grasping ends. When the 55 swinging frame begins its movement, the pin r^2 travels in the downwardly inclined part of the groove h^4 thereby moving the plunger down,—the end of said plunger striking the end of the die directly beneath it. At sub- 60 stantially the instant of contact the lower lugs r^6 move off of the bar r' , and the upper lugs r^5 engage with the upper beveled edge of said bar, and thereby the fingers are made to rock upon their pivots and grasp the said die just 65 below its head c^8 on its inner end. The further downward movement of the plunger moves the die outward to make its impression in the ma-

trix. The further movement of the swinging frame causes the pin r^2 to enter and move in the upwardly inclined part of the cam groove h^4 , thereby moving the plunger up and retracting the die. When the die is fully retracted, the lugs on the upper end of the fingers move off of the bar r' and the lower lugs r^6 engage with the lower edge of said bar, whereby the fingers are opened and the die released. When the swinging frame has completed its forward movement, the plunger is fully retracted and the pin r^2 is in the extreme left hand end of the cam groove. A spring actuated pin r^4 with beveled or rounded point enters a slight depression r^8 in the plunger, and prevents it from dropping by its own weight, and thus, when the swinging frame moves backward, the pin r^2 travels in the upper part of said groove passing over a spring switch h^5 to the position first described. The spring switch, h^5 is a pin which passes through the bracket h^3 , and projects into the upper part of the groove h^4 , and is pressed forward by a spring, as shown clearly in Fig. 27. The end of the pin which lies in the groove, is beveled on that side from which the pin r^2 , approaches it, whereby it is pushed back out of the way of said pin r^2 . When the pin r^2 has passed the switch, the switch springs forward and prevents the backward movement of said pin r^2 , in the upper part of the groove h^4 , thus compelling said pin r^2 , when it moves, to move in the descending part of the cam-groove h^4 , as first explained.

Below the bed plate A, a sliding bar I is supported in brackets a^9 a^9 , through which it may be caused to slide in the following manner: A coil spring i surrounds the bar and lies between the enlarged end i^3 and the bracket a^8 . The other end of this bar is permitted to play vertically in a slot in the bracket a^9 . On the under side of the forward end of this bar is a shoulder i' which, as the bar is moved forward, strikes a pin l on the arm of the bent lever L thereby rocking this lever sufficiently to release the keys as heretofore explained. When this lever has been moved far enough, an incline on the under side of the bar I strikes the bracket a^9 whereby the bar is lifted and the lever L is released; and this lever, through the action of the spring J^2 , immediately flies back to its normal position. An arm i^2 is rigidly secured to the bar or shoulder g^{17} on the under side of the swinging frame, when the frame is returning to its normal position. The frame moves the bar, as and for the purpose specified, while the bar acts as a spring buffer to check the backward movement of the frame.

The manner of securing the dies in the cylinder is substantially the same as is described in my prior patent, No. 475,804, that is to say,—rubber thimbles or bushings c are fastened in radial openings in the cylinder, and these bushings exert a pressure upon the dies which pass through them sufficiently to hold said dies stationary during the movements of the

wheel, when they are not being acted upon by the plunger. To avoid wear upon the rubber and friction in the sliding movements of the dies, the thin metal plates c' are interposed between the rubber bushings c and dies, such plates exerting no pressure upon the dies except such as is caused by the rubber bushings surrounding them.

The matrix holder T is secured to the bed 10 of the swinging frame. It is provided with two sides t t' between which the matrix slides, a bottom t^2 and a top plate t^3 having a funnel shaped opening t^4 which serves to guide and truly center the entering point of the die 15 should it start at one side of its true course.

The matrix indicated by S , and shown in Fig. 31, is of any suitable height, although I have found it convenient to make them type 20 high, and a trifle longer and thicker than the linotype to be cast therefrom.

U represents an inclined matrix hopper, which is secured to the carriage H , in which are placed a number of the matrix blocks with a weight against the bottom of the hopper. When the swinging frame is stationary, the entrance between the plates t t' of the matrix holder is directly in line with the bottom of the hopper. On the carriage are guides upon which a slide u moves; and to this slide 25 an arm u' is attached and so placed that when the slide is moved to the left this arm engages with the lowest matrix block in the hopper and pushes it into the matrix holder, thereby pushing out of the holder the matrix in 30 which the impressions have just been made. A lever u^3 pivoted to the carriage, engages with the slide and affords means for moving it.

In the operation of the machine, the matrix block is fed by the action of the die, in moving out against the matrix, a distance equal to the width of the character on the die, plus the normal space between two successive letters by substantially the same construction and arrangement of parts shown and described in my prior patent numbered 475,804. In this manner the impressions are automatically spaced according to the varying widths of the various letters and characters employed.

I will now describe the construction and arrangement of parts for properly feeding the matrix block. The dies are all of the same size, and the different sized characters thereon are all arranged with their rear or right hand ends at equal distances from the right side of their dies. Therefore, when the dies are in the cylinder, the rear or right hand ends of all the characters lie in the same vertical plane. On the forward side of each type-die, and integral preferably therewith, is a 45 projecting boss c^2 which, when the die descends, strikes the inclined face of a slide t^5 , which is mounted on the matrix holder. These projecting bosses c^2 are relatively proportionate to the width of the letters on the several dies; and, in the form shown, each projection is equal to the width of the letter plus the normal space between two adjacent letters;

thus each die, in descending upon the matrix, moves the slide a distance equal to the width of the letter thereon plus the inter-letter space. At the instant of this movement, the matrix block is in the embrace of devices connected with the slide, so that it moves in unison with the slide, as will be apparent from subsequent description. This movement of 75 the matrix block takes place immediately before the die begins to make its impression thereon, said die having some distance to move after it moves the slide. When the die is withdrawn, a spring t^6 returns the slide to its 80 first position.

I will now describe the devices by means of which the matrix block is grasped and compelled to move with the slide t^5 . Upon a concave surface of the carriage are cam 85 grooves h^6 . In a guide on the swinging frame is a sliding bar g^{18} having a downwardly turned pin g^{19} which enters said grooves. These parts are shown clearly in Fig. 19. Secured to an arm which is attached to the 90 slide t^5 is a spring plate t^7 having prongs t^8 on its end. When permitted to move freely this spring plate stands in such a position that the prongs do not touch the matrix block. Pivoted to an ear t^9 on the pressure piece t^{10} 95 is a bell crank lever t^{11} , and one arm of this lever is connected by the link t^{12} to the sliding bar g^{18} . On the other arm of the lever a friction roller t^{13} is placed which is adapted, when the lever is rocked, to press the spring 100 plate t^7 toward the matrix block and to cause the prongs thereon to strike into said block. If the slide be moved when the parts are in this position, the matrix will of necessity move in unison with it. When the lever is 105 rocked in the opposite direction the spring plate t^7 automatically withdraws its prongs from the matrix block. The pressure piece t^{10} is fastened to one end of a stiff piece of 110 spring metal, which is fastened at its other end to one of the sides of the matrix holder. Said pressure piece has a roughened surface at t^{14} which is adapted to strike against the side of the matrix block; and an overhanging finger t^{15} which rests on the edge of the top 115 face of the matrix block. A bracket t^{16} having an inclined surface is secured to the matrix holder and lies just above and in contact with an inclined surface on one arm of the lever t^{11} . When the swinging carriage begins 120 its movement, in fixed relation to the cylinder, the pin g^{19} on the sliding bar g^{18} is at the front end of the cam slot h^6 on the carriage, and neither the pressure piece t^{10} nor the spring plate t^7 is pressing upon the matrix 125 block, but when the pin g^{19} reaches the incline at h^7 , the bar g^{18} is moved, the lever t^{11} is rocked, and the prongs on the spring plate t^7 are forced, as above explained, into the matrix block. At this instant, the boss c^2 on the die begins to move the slide t^5 . The feed 130 movement of the slide has been completed before the pin g^{19} strikes the incline at h^8 which moves the bar g^{18} in the opposite di-

rection, thereby rocking the lever t^{11} and permitting the retraction of the spring plate t^7 . It also causes an incline on the lower arm of said lever t^{11} to strike an inclined surface on the bracket t^6 , whereby the pressure piece t^{10} is forced sidewise and downward against the matrix block, thereby forcing said block against the opposite wall and the lower plate of the matrix holder, where it is held until the die has made its impression in the matrix and the frame swings backward bringing the pin g^9 against the incline h^9 , which causes the pressure to be released. The matrix holding, feeding and clamping mechanism is clearly shown in Figs. 19, 20, 21, 22, 23, and 24. I prefer to place the dies bearing the lower case letters and some other characters in one row on the type wheel; those bearing the capitals, &c., in another row; those bearing the lower case italics in a third row; and those bearing the capital italics in a fourth row. Then by making the cylinder and the swinging frame relatively movable, any one of these series of letters may be used at will. This result is secured by the movement of the carriage which carries the swinging frame, and the parts connected with it (and in fact nearly all of the parts of the machine except the cylinder and key board mechanism as before explained). The carriage is moved by means of a lever O pivoted to the main frame. It is provided with a latch O^2 adapted to engage with the notches in the plate O' , which notches are so arranged that when the latch engages with one of them one of the rows of dies is in the plane of the plunger R and guide t^4 of the matrix holder. As a safeguard to prevent injury of the parts by reason of any failure to properly lock the carriage, I secure to the carriage a bar J' having four notches j each adapted to certain positions of the carriage to receive the lower end of the lever J whenever a key is struck. If the carriage is not in one of the four correct and operative positions, the lever cannot enter one of the notches j and the key cannot therefore be depressed far enough to produce any effect on the other parts of the machine. In this movement of the carriage, the plate g^7 and latch g^{11} slide freely on the rod g^6 always preserving the same relation with the cylinder without affecting their operative connection with the swinging frame. The machine is also provided with a typewriter attachment which I will now proceed to explain, whereby a proof or type written fac simile of the impressions made in the matrix block is simultaneously made on paper which may be read by the operator.

Fixed to the cylinder, and projecting radially therefrom, are one or more fonts of type F arranged in rows which correspond to the rows of dies heretofore explained. These type are preferably made of rubber, and are set into sockets in the cylinder, but project therefrom far enough to extend through the funnel shaped guide, to be hereinafter explained,

and against the paper behind it. Abreast of this part of the cylinder is a frame M which supports the laterally movable vibrating part carrying frame.

Two brackets $V^1 V'$ are secured to the swinging matrix carrying frame; and to these brackets are rigidly fastened the four horizontal bars $V^2 V^3$ and $V^4 V^5$. These four bars are likewise connected to a yoke V^6 whereby they are held in fixed relation to each other. To the bars $V^4 V^5$ the two side pieces $m m'$ are rigidly fixed, and to the upper ends of said side pieces a horizontal bar m^2 is fixed. A frame M' consisting of the side pieces $m^3 m^4$ and a connecting cross bar m^5 is pivoted by pivots at $m^6 m^6$ to the side pieces $m m'$, whereby said frame may be swung toward and from the cylinder.

N represents a laterally movable frame which is mounted and adapted to slide upon the bars $V^5 m^2 m^5$. The upper part of this frame is pivoted to the lower part by pivots in line with the pivots $m^6 m^6$ whereby it may swing toward the cylinder in unison with the frame M' . To the upper ends of the side bars $n n'$ of the laterally movable frame N are mounted the platen roll n^2 and the rolls $n^3 n^4 n^5$ for holding and feeding the paper and the copy.

An arm P , composed of two parts pivoted together, is fastened to the bar V^4 . On the upper end of the upper part is a funnel shaped guide P' which is adapted to set down over one of the types F , and guide it against the paper on the platen. The upper part is pivoted to the lower part so that the funnel shaped guide may swing away from the type when the cylinder is moving independently of the swinging matrix carrying frame. A spring P^2 produces this backward movement which is only sufficient for the intended purpose. On one side of the vibrating frame M' is an arm m^{10} to which one end of a spring m^7 is connected. The other end of the spring is connected with the side piece m' and the function of the spring is to swing the frame M' away from the cylinder.

On a projection m^9 from the other side of the vibrating frame is an arm m^8 to which is loosely pivoted a lever W . The lever is free to swing in one direction without any effect on the described mechanism; but when swung in the opposite direction, its upper end strikes said projection m^9 and swings the frame M' toward the cylinder. In this movement, the frame strikes the arm P bearing the funnel shaped guide P' , forces it over one of the type which is then impressed upon the paper.

When the swinging matrix carrying frame has been connected with the cylinder, as heretofore explained, and is therefore moving in fixed relation thereto, this type writer attachment being supported by said swinging frame is moving in unison with it. A bent arm h^9 is secured to the standard h , and in each forward movement of the swinging frame, the lever W strikes this arm thereby causing the

paper carrying frame N to be moved toward the cylinder with the above described result. The imprint upon the paper is made at about the same instant that the die is being impressed in the matrix, as shown in Fig. 4. The continued forward movement of the matrix carrying frame frees the lever W from its engagement with the arm h⁹; and in the return movement of said frame, the lever W is turned back and passes said arm h⁹ without any effect on the other mechanism. A spring W' returns the lever to a position where in the next movement of the frame the same action is repeated. Immediately after the lever W passes the arm h⁹, during the forward movement of the matrix carrying frame, the spring m⁷ swings out pivoted frame M' and N so that the operator can see whether the correct letter has been printed on the paper. To the upper end of the paper carrying frame are journaled the platen roll n² and a roll n⁴ for holding the copy, and two rolls n³ n⁵ which serve to hold the two pieces of paper on said rolls. Two inking ribbon rolls n⁶ n⁷ are carried by the arm P, and the ribbon n⁸ passes between the funnel shaped guide and the platen roll.

The paper carrying frame is connected with the matrix by mechanism which I will now describe, whereby the frame is fed along equally and simultaneously with the matrix. Fastened to the laterally moving paper carrying frame is an arm N' which passes between the two bars V²-V³, whereby it is held in proper position relative to the parts it is intended to engage with. On its outer ends are secured two small rods n⁹ and n¹⁰ between which a pin Y projects. This pin is attached to a slide Y' which is suitably guided in a path parallel to that traveled by the matrix. Pivoted to this slide is a spring actuated arm Y² having prongs on its end which project through the side wall of the matrix holder and stick into the matrix block. When, therefore, the matrix is fed along as before explained, it drags the paper carrying frame with it. When the matrix is fed along to the position to receive the last letter of a line, the beveled end of the arm Y² strikes against the beveled surface at t¹⁷ on the matrix holder T, whereby the said arm Y² is swung outward enough to withdraw from the matrix block the prongs on the end of said lever. The paper carrier may now be moved back to its first position by hand; or by suitable mechanism which may be provided for the purpose. In moving backward the paper carrier draws back the slide Y'. In this backward movement of the slide, a pin Y³, depending from the spring arm Y², engages on the outside of the rail Z which holds the prongs away from the new matrix block which has been introduced into the holder; and when near the end of its backward journey, the pin slides up the inclined surface Z' on said rail, thereby swinging the arm Y² outward and applying tension to the spring which actuates said arm. When

the pin is moved off of this incline surface, the spring causes the arm Y² to fly down with such force that the prongs are embedded in the matrix, thus making connection, as before explained, between said matrix and paper carrier.

Having thus described my invention, what I claim as new, and desire to secure by Letters Patent, is—

1. In a matrix making machine, in combination, a cylinder, a plurality of rows of radially movable dies carried thereby, a sliding carriage, a matrix carrier supported by said carriage, die actuating mechanism likewise supported on said carriage, and mechanism to move said carriage, whereby the die actuating mechanism and matrix carrier are simultaneously moved into line with the dies in any row, substantially as set forth.

2. In a matrix making machine, in combination, a revolving cylinder having a plurality of rows of radially movable dies, a movable carriage, a swinging matrix carrier, mounted on said carriage concentrically with said cylinder, die actuating mechanism likewise supported by said carriage, and mechanism for moving said carriage whereby the die actuating mechanism and matrix carrier may be simultaneously moved to a position where a die in any row may be moved outward against the matrix, substantially as set forth.

3. In a matrix making machine, in combination, a revolving cylinder carrying radially movable dies, a swinging matrix carrier mounted concentrically with said cylinder, means for moving said carrier in fixed relation to said cylinder, a plunger mounted on said matrix carrier, and a fixed cam engaging with said plunger, whereby the plunger is moved during the time the carrier is moving forward, substantially as and for the purpose specified.

4. In a matrix making machine, in combination, a revolving hollow cylinder, radially movable dies carried thereby, a swinging matrix carrier mounted concentrically with said cylinder, means for moving said matrix carrier in fixed relation to said cylinder, a plunger carried by said matrix carrier, gripping fingers pivoted to said plunger each having a lug above and another below its pivot, a bar having beveled edges which engage with said lugs, and a fixed cam which engages with and operates said plunger, substantially as set forth.

5. In a matrix making machine, in combination, a revolving cylinder, a series of radially movable dies carried thereby, a swinging matrix carrier, means for moving it in fixed relation to the cylinder, a radially movable plunger mounted on said matrix carrier, a pin projecting therefrom, a fixed cam groove into which said pin projects, and a spring switch for guiding said pin, substantially as set forth.

6. In a matrix making machine, in combination, a revolving cylinder having a plurality of rows of radially movable dies, a sliding

carriage, a matrix carrier mounted thereon, a notched rod secured to said carriage, a series of finger keys, and a lever J actuated by each of said finger keys, substantially as and for the purpose specified.

7. In a matrix making machine, a revolving cylinder, a series of longitudinally movable rods carried thereby, a series of finger keys, means whereby the depression of any finger key moves its corresponding rod and causes it to project beyond the end of the cylinder, a swinging frame mounted concentrically with said cylinder having a shoulder with which the projecting rod engages, thereby causing the frame and cylinder to move in unison, and means for withdrawing said rod, substantially as set forth.

8. In a matrix making machine, in combination, a revolving cylinder, a series of longitudinally movable rods adapted to project from the end of said cylinder, key mechanism for actuating said rods, a swinging frame, a locking plate and a latch carried by said frame and adapted to engage with a projecting rod, substantially as set forth.

9. In a matrix making machine, in combination, a revolving hollow cylinder, a concentrically pivoted swinging frame, one of said parts being longitudinally movable with respect to the other, said cylinder having near its end an annular flange, a rod g^6 carried on the swinging frame, a plate g^7 slidable on said rod having the flanges g^9 , and pin g^8 , and shoulder g^{10} , longitudinally movable rods carried by said cylinder and means for projecting any of said rods from the end of said cylinder, substantially as set forth.

10. In a matrix making machine, in combination, a revolving cylinder, a series of longitudinally movable rods, mechanism for projecting one of said rods from the end of the cylinder, a concentrically pivoted swinging frame, locking mechanism for holding said frame in its normal position, a locking plate carried by said frame, and adapted to engage with the projecting rod, and mechanism con-

nnecting said plate and locking mechanism, whereby the frame is released from said mechanism by the engagement of the rod with the plate, substantially as set forth.

11. In a matrix making machine, in combination, a revolving cylinder, a series of longitudinally movable rods mounted thereon, mechanism for projecting one of said rods from the end of the cylinder, a concentrically pivoted swinging frame, a rock shaft g^3 on said frame, a frame secured to the rock shaft, a plate g^7 having a shoulder g^{10} , a toe g^{14} , and a spring actuated locking arm h^2 , substantially as set forth.

12. In a matrix making machine, in combination, a revolving cylinder, radially movable dies, and radial type both carried by said cylinder, a swinging matrix carrier mounted concentric with said cylinder, means for moving the matrix carrier at intervals in fixed relation to said cylinder, a paper carrying frame secured to said swinging matrix carrier, and means for moving the paper carrying frame toward the cylinder during the time the matrix carrier and cylinder preserve their fixed relation, substantially as set forth.

13. In a matrix making machine, a revolving cylinder consisting of two parts one fixed to a shaft, means for connecting and disconnecting said two parts, and a series of radially movable dies carried by said removable part of the cylinder, substantially as set forth.

14. In a matrix making machine, in combination, a swinging matrix carrying frame, a series of finger keys, a device for locking the keys when one has been depressed, key releasing mechanism arranged in position to be actuated by the swinging frame on its return movement, substantially as set forth.

In testimony whereof I affix my signature in presence of two witnesses.
